(57) **CLAIM**

(21) Appl. No.: **29/214,159**

The ornamental design for an electrode for a plasma torch, as shown and described.

(22) Filed: **Sep. 29, 2004**

DESCRIPTION

(30) **Foreign Application Priority Data**

Mar. 31, 2004 (JP) 2004-009842

FIG. 1 is a front view of our electrode for a plasma torch showing our design.

(51) **LOC (8) Cl.** **15-09**

FIG. 2 is a top plan view of our electrode;

(52) **U.S. Cl.** **D15/144**

FIG. 3 is a right side view of our electrode;

(58) **Field of Classification Search** D15/139,

D15/144—144.2; 219/121.44—121.5; 313/231.31

See application file for complete search history.

FIG. 4 is a left side view of our electrode; and,

(56) **References Cited**

FIG. 5 is a perspective view of our electrode.
